Primary Examiner—Paula Greene

(57) **CLAIM**

The ornamental design for an earphone cover, as shown and described.

DESCRIPTION

FIG. 1 is a front view of an earphone cover showing my new design;

FIG. 2 shows a rear view of the earphone cover.

FIG. 3 shows a top view of the earphone cover.

FIG. 4 shows a bottom view of the earphone cover.

FIG. 5 shows a left view of the earphone cover.

FIG. 6 shows a right view of the earphone cover.

FIG. 7 is a left view of an earphone thereof; and,

FIG. 8 is a front view of an earphone cover thereof.

The broken lines in FIGS. 1, 7 and 8 form no part of the claimed design.
